Primary Examiner — Paula Allen Greene(74) *Attorney, Agent, or Firm* — Kunzler Bean & Adamson, PC; Alandra Adams(57) **CLAIM**

The ornamental design for combined phone stand and speaker, as shown and described.

DESCRIPTION

FIG. 1 is a front, left and top perspective view of a combined phone stand and speaker, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another rear, right and bottom perspective view thereof, in an alternate position.

FIG. 10 is an enlarged view of detail 10 in FIG. 1.

FIG. 11 is an enlarged view of detail 11 in FIG. 2.

FIG. 12 is an enlarged view of detail 12 in FIG. 3; and, FIG. 13 is an enlarged view of detail 13 in FIG. 3.

The broken lines depict portions of the combined phone stand and speaker that form no part of the claimed design. The dot dash broken lines encircling portions of the combined phone stand and speaker in FIGS. 1, 2, and 3 and illustrated in the enlarged views of FIGS. 10, 11, 12, and 13 form no part of the claimed design.
